UNITED STATES PATENT OFFICE.

CHARLES F. COPELAND, OF BOSTON, MASSACHUSETTS, ASSIGNOR TO SOPHIA E. COPELAND, OF SAME PLACE.

CARBURETOR.

SPECIFICATION forming part of Letters Patent No. 274,176, dated March 20, 1883.

Application filed January 4, 1883. (No model.)

To all whom it may concern:

Be it known that I, CHARLES F. COPELAND, a citizen of the United States, residing at Boston, in the county of Suffolk and State of Massachusetts, have invented certain new and useful Improvements in Carburetors; and I do hereby declare that the same are fully described in the following specification and illustrated in the accompanying drawings.

10 This invention relates to improvements in carburetors, and it is carried out as follows, reference being had to the accompanying drawings, where—

Figure 1 represents a plan view, and Fig. 2 a 15 central longitudinal section, of my improved apparatus.

Similar letters refer to similar parts wherever they occur on the different parts of the drawings.

20 The invention consists of a metallic cylinder, *a*, to the inside of which is cemented or otherwise secured a felt lining, *b*, which latter serves as a packing for the Archimedean screw *c*, the outer edge of which is screwed into and made 25 to project slightly into the body of said felt lining *b*, so as to make a tight joint between the outer edge of the screw *c* and the inside of the felt lining *b*, the latter serving, as it were, as a female screw-thread, into which the screw 30 *c* is screwed, as shown in Fig. 2. The bottom of the cylinder *a* has secured to it a circular plate, *a'*, on which the lower end of the screw *c* rests, as shown, said plate being provided 35 with a perforation, *a''*, through which the gas and air that are to be enriched are forced upward in a spiral manner through the screw *c*, they being prevented from passing between the exterior edge of said screw and the inside of cylinder *a* by the arresting packing medium *b*, as 40 before described. The cylinder *a* has an exterior flange, *a³*, in its lower end, to which is secured air-tight the flange *d'* of the hollow chamber *d*, into which enter the ends of the air-pipe *e* and gas-pipe *f*, the upper ends of said pipes 45 being provided with suitable hoods, *e'* and *f'*, respectively, to prevent any descending liquid hydrocarbon from dropping into said pipes *e* and *f*. The cylinder *a* and chamber *d* are supported on suitable legs or bases, *g g g*, resting on 50 the floor or ground.

Below the cylinder *a*, which constitutes the

carburetor, is located the tank or receptacle *h* for the liquid hydrocarbon *h'*, as shown in Fig. 2.

i is a suitable steam or air pump, provided 55 with a suction-pipe, *i'*, passing downward through the tank *h* and terminating near the bottom of the latter.

i'' is the force or delivery pipe leading from pump *i* to the upper end of cylinder *a*, where 60 it terminates as a nozzle, *i³*, located above the upper end of the screw *c*, as shown in Fig. 2, and by which means the liquid hydrocarbon is drawn from below and delivered at the upper end of the screw *c*, and follows the spiral wall 65 of the said screw *c* as it flows downward against the spirally-ascending gas and air from the pipes *e f*, thus presenting in a small compass a very large evaporating-surface, by which the 70 ascending gas and air are homogeneously and rapidly enriched.

Should more hydrocarbon be pumped up into the upper part of cylinder *a* than what is taken up by the gas and air, such surplus liquid is automatically returned through the trap-pipe *k*, leading from lower chamber, *d*, to the 75 receptacle or tank *h*, as shown in Fig. 2.

l is a transparent glass pane set into the side of the upper part of cylinder *a*, opposite to the nozzle *i³*, by means of which the proper flow 80 of the liquid through such nozzle can be ascertained by looking through such pane or window.

a⁴ is the exit-opening in the upper end of cylinder *a*, through which the enriched gas and 85 air pass to a suitable regulator, *m*, and delivery-pipe *m'*, leading to the burners.

e' is a suitable regulator, and *e''* a suitable back-pressure valve in the air-pipe *e*, as usual, to prevent the escape of gas through said air-pipe.

The air is forced through pipe *e* and into and up through cylinder *a* by means of a suitable fan-blower, as usual.

The object of introducing a small percentage 95 of air in addition to the gas is to reduce the richness of the enriched gas, and by so doing I am enabled to use the same sized burners as are used when ordinary street-gas is burned, and two important results are thereby accomplished—namely, I prevent the gas from smoking and prevent all condensation in the pipes,

which sometimes occurs when gas is very highly enriched by hydrocarbon alone.

I regulate the amount and pressure of the gas and air entering the cylinder *a* by means of any proper gas governor or regulator, and when the enriched vapor ascends and escapes from the upper end of the cylinder it enters a suitable governor connected therewith, as described, and which regulates its discharge into the supply-pipe for the burners.

I regulate the amount of liquid hydrocarbon entering the cylinder *a* by means of any proper valve, which, when once set, allows the right amount to flow over the spiral surface of the screw *c*.

The operation of this my improved carburetor is as follows: The hydrocarbon is pumped by means of the pump *i* from the tank *h* and expelled through the nozzle *i'* in the upper end 20 of the cylinder *a*, above the upper end of the Archimedean screw *c*, and flows downward spirally on said screw in the form of a thin sheet, and in so doing descends spirally in an opposite direction to the spirally-ascending gas 25 and air, which are forced upward through the pipes *e* and *f*, heretofore described, and in so doing the gas and air are brought in very intimate contact with a very large surface of the liquid hydrocarbon, and are thus rapidly enriched by the volatile products of the hydrocarbon. Should more of the hydrocarbon be delivered at the upper end of the cylinder *a* than is taken up by the gas and air, the sur-

plus will be automatically conducted back again to the tank *h* through the trap-pipe *k*, 35 as described. The gas and air, after being properly mixed and enriched, as described, are forced out through the delivery-pipe *m'* to the burners, as above described.

By the construction and arrangement as 40 herein shown and described several advantages over the ordinary carburetors are obtained, among which may be mentioned the arrangement of the carbureting-chamber above the hydrocarbon-tank, which enables the latter to be placed in the basement or under 45 ground outside of the building, so as to be entirely out of the way.

What I wish to secure by Letters Patent and claim is—

1. The herein-described carburetor, consisting of the cylinder *a*, its internal felt packing, *b*, and Archimedean screw *c*, as and for the purpose set forth.

2. In a carburetor, the lower hydrocarbon receptacle, *h*, and upper chamber, *a*, with its felt packing *b* and Archimedean screw *c*, in combination with the pump *i*, pipes *i' i''*, air and gas pipes *e f*, and return trap-pipe *k*, as and for the purpose set forth.

In testimony whereof I have affixed my signature in presence of two witnesses.

CHARLES F. COPELAND.
